UNITED STATES PATENT OFFICE.

ENOCH P. STEVENS, OF CHICAGO, ILLINOIS, ASSIGNOR, BY MESNE ASSIGNMENTS, TO
AMERICAN ARCH COMPANY, OF NEW YORK, N. Y., A CORPORATION OF DELAWARE.

LOCOMOTIVE-ARCH.

1,229,381.

Specification of Letters Patent. Patented June 12, 1917.

Application filed March 31, 1913, Serial No. 757,822. Renewed January 10, 1916. Serial No. 71,378.

To all whom it may concern:

Be it known that I, ENOCH P. STEVENS, a citizen of the United States, residing at Chicago, in the county of Cook and State 5 of Illinois, have invented certain new and useful Improvements in Locomotive-Arches, of which the following is a specification.

My invention relates to arches of refractory fire-brick used in the fire-boxes of locomotives. The particular style of arch which 10 forms the subject-matter of my invention is of the type usually known as the front arch, this arch being supported on arch tubes extending longitudinally through the fire-box and sloping downwardly from the rear of the fire-box to the lower portion of the flue-sheet.

Heretofore two principal types of front arches supported on arch tubes have been 20 employed: first, arches in which a portion of the space between each of the outer arch tubes and the side sheet of the fire-box was filled by extensions of the bricks forming the two outer rows of the arch, each of these 25 rows being supported on two arch tubes; second, arches in which there were several rows of bricks each supported between adjacent arch tubes (thus forming three rows of bricks if four arch tubes were used), and 30 separate side rows of bricks between the outermost arch tubes and respective side sheets, these side bricks being supported by the joint action of the side sheets and the outer arch tubes or the bricks supported thereon.

It has been found by experience that there 35 are marked disadvantages about each form of arch which I have just described. In the first type of arch it is necessary to employ bricks of great length which are difficult to 40 handle and very liable to breakage. In arches of the second type the vibration of the side sheets is transmitted through the side bricks to the arch, and causes undue vibration of the latter, while at the same 45 time the side rows of bricks are very apt to become displaced at one end or the other and fall down onto the bed of fuel.

In my improved form of arch I avoid the 50 difficulties of both types of arches which have been described above. I employ a plurality of main rows of bricks, the bricks of each row being supported at their opposite ends by arch tubes, each row of bricks being substantially the width of the space 55 between adjacent tubes. In this way I am

able to employ bricks of such dimensions that they are not liable to breakage. The side rows of bricks which partially fill the spaces between the outer arch tubes and the side sheets constitute what I term the cantaliver bricks, since these latter bricks are supported by the adjacent main rows of bricks or by the joint action of such bricks and the outer arch tubes, and are not supported by nor do they rest against the side sheets 60 of the fire-box. It will be evident that as the side bricks are supported in this manner they constitute cantaliver structures. In this way the transmission of the vibrations of the side sheets to the arch is avoided, and, 65 moreover, the chance of having the bricks displaced and fall down onto the fuel bed is greatly decreased.

These and other advantages of my invention will be more readily understood by 70 reference to the accompanying drawings, which show preferred embodiments of my invention, and in which:

Figure 1 is a vertical transverse section through a locomotive fire-box, taken on the line 1—1 of Fig. 2;

Fig. 2 is a vertical longitudinal section through the fire-box, taken on the line 2—2 of Fig. 1;

Fig. 3 is a transverse vertical section taken 85 on the line 3—3 of Fig. 2;

Fig. 4 is a fragmentary plan of the arch shown in Fig. 3;

Fig. 5 is a perspective of a brick of one 90 of the main rows used in the form of arch illustrated in Fig. 3;

Fig. 6 is a perspective of a side brick used 95 in the arch construction shown in Fig. 3;

Fig. 7 is a section similar to Fig. 3 but showing a modified form of arch construction;

Fig. 8 is a fragmentary plan of a second modified form of arch construction; and,

Fig. 9 is a vertical transverse section, taken on the line 9—9 of Fig. 8.

The arch tubes 20, of which there are generally four, extend longitudinally through the fire-box 21, sloping downwardly from the water leg 22 at the rear of the fire-box to the water leg 23 at the front thereof. 105 The sleet 24 to which the front ends of the tubes 20 are attached constitutes the rear flue-sheet of the locomotive.

On its sides the fire-box is bounded by the side sheets 25 outside of which are the water 110

legs 26. At the top of the fire-box the side sheets 25 are joined to form the crown sheet 27.

In the form of arch illustrated in Figs. 5 to 6, inclusive, the central row of bricks 28 is supported at its edges by the two central arch tubes 20. These bricks 28 are of well-known shapes and functions and fit down between the arch tubes 20. The bricks 10 of the rows supported between the two outer arch tubes on each side are of the type shown most clearly in Fig. 5. Each of these bricks 29 has a socket 30 in one edge, this socket engaging an arch tube 20. On its opposite 15 end the brick 29 is provided with a tongue 31, which is preferably of approximately half the total width of the body of the brick. The under surface of the tongue 31 has the socket 32, which engages the outer arch tube 20. It is evident that a portion of this 20 tongue extends laterally slightly beyond the outer arch tube, as clearly illustrated in Figs. 1, 3 and 4. Each side of the tongue 31 is provided with a groove 33. As best 25 shown in Fig. 4, when the bricks 29 are placed in position, a space is left between the adjacent tongues 31, this space being approximately the same width as that of one of the tongues 31.

30 The shape of the cantaliver bricks of the side rows is best shown in Fig. 6. Each brick 34 has a body portion 35, which preferably extends upwardly toward the side sheet and gradually tapers toward said sheet. Integral with the body portion 35 is the tongue 36, having on its bottom the semi-circular groove 37 adapted to engage an outer arch tube 20. On the sides of the tongue 36 are the locking ribs 38. As shown 35 in Figs. 1, 3 and 4, the tongue 36 of each of the cantaliver bricks 34 is placed in position between the tongues 31 of the bricks 29, the locking ribs 38 engaging the grooves 33 of the tongues 31. In this way the cantaliver bricks 34 are securely held in position. The outer edges of these bricks 34 are clear 40 of the side sheets 25, thus preventing the transmission of vibration from the side sheets to the arch. If desired, the corners 50 of the side or marginal bricks may be cut off, as shown in Fig. 8, thereby providing more space in certain portions between the side bricks 34 and the side sheets 25. This is often of advantage to prevent the accumulation 55 of cinders on the arch itself.

In Fig. 7 I have shown a slightly modified form of construction. In this case the arch is made up of a pair of rows of the bricks 39, the bricks of each of these rows resting on the two outer arch tubes. The bricks 39 are upwardly beveled on their inner ends, and between them is supported a row of wedge-shaped bricks 40, having downwardly beveled ends which rest against the corresponding beveled ends of the bricks 39. The outer

ends of bricks 39 are formed with tongues 41 corresponding to the tongues 31 of the bricks 29, formerly described. In this style of arch the cantaliver bricks 34 are of exactly the same shape as described in connection with the arch illustrated in Figs. 1 to 6, inclusive. The cantaliver bricks are securely locked in position, and the socket or groove 37 in the tongue 36 of each of the cantaliver bricks serves to prevent lateral 75 movement of the arch as a whole, and also prevents spreading of the bricks 39 by reason of the wedging action of the bricks 40.

In Figs. 8 and 9 I have illustrated another modified form of construction for the 80 cantaliver bricks and the bricks of the rows immediately adjacent to the cantaliver bricks. Each of the bricks 42 of this form of arch rests on two of the outer arch tubes 20, the bottoms of the bricks preferably being 85 on a line with the upper surface of the arch tubes, although if desired bricks may be used which have sockets in their edges, and so fit down between the arch tubes, in the manner illustrated in Fig. 3. 90

Each of the bricks 42 has a tongue 43 which rests directly on an arch tube 20. On each side of the brick between the tongue 43 and the edge of the brick is provided a beveled surface 44, while the outer edge of the 95 tongue 43 is provided with the ledge 45, which preferably slopes inwardly, for the purpose presently to be described.

Each of the side cantaliver bricks 46 has a tongue 47 which is adapted to fit into the 100 space between the tongues 43 of the bricks 42, as best shown in Fig. 8. The inner edge of the tongue 47 is provided with a beveled surface 48 adapted to engage the beveled surfaces 44 of two adjacent bricks 42. Between the tongue 47 of each side brick 46 and the edges of the brick are provided the 105 abutments 49 adapted to rest on the ledges 45 of the bricks 42. On account of the fact that the ledges 45 slope inwardly, they serve 110 as locking means for preventing outward movement of the cantaliver bricks 46. On the bottom of each brick 46 is preferably provided a lug 50 which engages the arch tube 20 and prevents outward movement of the 115 bricks 42 and the side bricks 46, the bricks 46 on the two sides of the arch thereby securely locking the latter in position.

In installing the arch it will be evident 120 that the bricks 42 are first placed in position, and the cantaliver bricks 46 may then be readily adjusted.

It will be apparent to those skilled in the art that many changes can be made in the detailed construction of the arch which I have described, without departing from the spirit or scope of my invention. 125

The several modifications of my invention which are embraced in and suggested by the structures disclosed in Figs. 8 and 9 of the 13

drawings are not specifically claimed in this application, but constitute the subject matter of a divisional application, Serial Number 77,647, filed February 11th, 1916.

8. What I claim is:

1. In a locomotive arch construction, the combination with a fire-box having a plurality of arch tubes extending therethrough, of a plurality of rows of bricks supported on 10 said tubes, and a row of cantaliver bricks extending into the space between each of the outer tubes and the side sheets of the fire-box, said cantaliver bricks being out of contact with said side sheets, substantially as described.
15. 2. In a locomotive arch construction, the combination with a fire-box having a plurality of arch tubes extending therethrough, of a plurality of main rows of bricks supported 20 on said tubes, and a row of cantaliver bricks extending into the space between each of the outer tubes and the side sheets of the fire-box, each of said cantaliver bricks being supported by the joint action of the bricks 25 of the adjacent main row and an outer arch tube and being out of contact with said side sheets, substantially as described.
3. In a locomotive arch construction, the combination with a fire-box having a plurality 30 of arch tubes extending therethrough, of a plurality of main rows of bricks supported on said tubes, a row of cantaliver bricks extending into the space between each of the outer tubes and the side sheets of the 35 fire-box, each of said cantaliver bricks having a tongue extending therefrom, and means for forming locking engagement between said tongue and the bricks of the adjacent main row, substantially as described.
40. 4. In a locomotive arch construction, the combination with a fire-box having a plurality of arch tubes extending therethrough, of a plurality of main rows of bricks supported on said tubes, and a row of cantaliver bricks extending into the space between each of the outer tubes and the side sheets of the 45 fire-box, each of said cantaliver bricks engaging the bricks of the adjacent main row and being out of contact with said side sheet, substantially as described.
5. In a locomotive arch construction, the combination with a fire-box having a plurality 50 of arch tubes extending therethrough, of a plurality of rows of bricks supported on said tubes, a row of cantaliver bricks extending into the space between each of the outer tubes and the side sheets of the fire-box, said cantaliver bricks being out of contact with said side sheets, and means for preventing lateral movement of said arch, substantially as described.
6. In a locomotive arch construction, the combination with a fire-box having a plurality 55 of arch tubes extending therethrough, of a plurality of main rows of bricks sup-
- ported on said tubes, a row of cantaliver bricks extending into the space between each of the outer tubes and the side sheets of the fire-box, each of said cantaliver bricks engaging the bricks of an adjacent main row and being out of contact with said side sheets, and means for preventing lateral movement of said arch, substantially as described. 70
7. In a locomotive arch construction, the combination with a firebox having supporting means extending therethrough, of a main brick resting on said supporting means, and a cantaliver brick having locking engagement with said main brick. 75
8. In a locomotive arch construction, the combination with a firebox having a plurality of arch tubes extending longitudinally therethrough, of a main brick supported on said tubes, a cantaliver brick extending into the space between one of said tubes and the side sheet of the firebox, and means for forming locking engagement between said main brick and said cantaliver brick. 80
9. In a locomotive arch construction, a firebox and its side sheets and a plurality of arch tubes some of which substantially parallel said side sheets, in combination with a main arch brick having its outer end on 95 one of said tubes adjacent said side sheet and a cantaliver brick extending from the end of said main brick nearly across the space between said tube and side sheet and positively held out of contact with said side sheet. 100
10. In a locomotive arch construction a fire-box side sheet, and an arch tube substantially paralleling the same, in combination with a main arch brick having its outer 105 end supported by said tube, a second brick extending therefrom substantially across the space between said sheet and tube, the ends of said bricks being interlocked in a manner to positively hold the free end of the 110 second brick out of contact with said side sheet.
11. In a locomotive arch construction a fire-box side sheet and an arch tube substantially paralleling the same, in combination with a main arch brick having its outer end supported by said tube, a second brick extending therefrom substantially across the space between said sheet and tube, the ends 115 of said bricks being separately interlocked in a manner to positively hold the free end of the second brick out of contact with said side sheet. 120
12. In a locomotive arch construction a fire-box side sheet and an arch tube substantially paralleling the same, in combination with a main arch brick having its outer end supported by said tube, a second brick extending therefrom substantially across the space between said sheet and tube, the ends 125 of said bricks being interlocked in a manner to positively hold the free end of the second brick out of contact with said side sheet. 130

of said bricks being separably interlocked in a manner to positively hold the free end of the second brick out of contact with said side sheet, and said tube constituting part of the means assisting to retain said bricks in interlocked engagement.

13. In a locomotive arch construction, a firebox side sheet and a water-circulating arch tube substantially paralleling the same, in combination with a main arch brick and a cantaliver brick both resting upon said tube and both interlocked therewith, and means detachably but rigidly joining the ends of said bricks, whereby said cantaliver brick is held in fixed relation to said brick said tube and said sheet.

14. In a locomotive arch construction, two main bricks arranged side by side as upon an arch tube, in combination with a cantaliver brick having its end in abutment with both said main bricks and said bricks being provided with complementary tongues, which are interlocked and fix the relations of said main and cantaliver bricks.

15. In a locomotive arch construction, two main bricks arranged side by side as upon an arch tube, in combination with a cantaliver brick having its end in abutment with both thereof, all said bricks being provided with complementary tongues which are interlocked and fix the relations of said main and cantaliver bricks, and the undersides of all said bricks being socketed to fit the top of an arch tube.

ENOCH P. STEVENS.
